Specification for Design.

Patented Dec. 10, 1918.

Application filed February 8, 1918. Serial No. 216,119. Term of patent 7 years.

To all whom it may concern:

Be it known that I, PHILIPP SILBERMANN, a citizen of the United States, and a resident of New York, borough of Manhattan, in the county of New York and State of New York, have invented a certain new, original, and ornamental Design for Jewel-Settings, of which the following is a specification.

The accompanying drawing illustrates my new design for jewel setting, wherein—

Figure 1 is a top plan view of a jewel-setting illustrating my new design; Fig. 2 is a bottom plan view thereof; Fig. 3 is a side view of the same; and Figs. 4 and 5 are sectional views, Fig. 5 being 30° turned from Fig. 4.

I claim:

The ornamental design for a jewel setting, as shown.

PHILIPP SILBERMANN.
